SELECTOR SWITCH

William Correll Edwards and Scott R. Conwell,
Anderson, Ind., assignors to General Motors
Corporation, Detroit, Mich., a corporation of
Delaware

Original application August 16, 1933, Serial No.
685,500, now Patent No. 2,059,780, dated No-
vember 3, 1936. Divided and this application
December 24, 1935, Serial No. 56,018

4 Claims. (Cl. 200—11)

This invention relates to selector switches and more particularly to switches of the rotary type which are adapted to be mounted adjacent the lower end of a steering column of an automobile and to be operated by a shaft extending through the steering column and actuated from the upper end thereof. This is a division of our copending application filed August 16, 1933, Serial Number 685,500, now Patent Number 2,059,780, patented November 3, 1936.

An object of the present invention is to provide a cover or enclosure for the switch terminal connections to protect the terminal connections from adverse weather conditions, and in which the cover may be removed for ready inspection of the terminal connection without disturbing their relative association.

Another object of the invention is to provide a selector switch that will provide for interchange of lighting element of a lighting system in accordance with varying conditions and statutory regulation necessitating illumination. This has been accomplished by providing a switch construction having a plurality of contacts arranged in circular rows to which contact portions of electrical circuits are connected.

Further objects and advantages of the present invention will be apparent from the following description, reference being had to the accompanying drawings wherein a preferred embodiment of one form of the present invention is clearly shown.

In the drawings:

Fig. 1 illustrates in side elevation, a selector switch embodying the instant invention.

Fig. 2 illustrates in bottom plan view, a selector switch substantially as indicated by the arrow 2 of Fig. 1.

Fig. 3 is an exploded view of a selector switch construction, depicting the contributing parts in their relative positions when assembled.

Fig. 4 is a rear view of the switch back, or contact and terminal support, substantially as indicated by the arrow 4 of Fig. 5.

Fig. 5 is a sectional view through the selector switch substantially as indicated by the line and arrows 5—5 of Fig. 2.

Fig. 6 is a plan view of the contact side of the switch back, substantially as indicated by the line and arrows 6—6 of Fig. 5.

Fig. 7 is a detail view in plan, of the movable contact assembly substantially as illustrated by the line and arrows 7—7 of Fig. 5.

Fig. 8 is a transverse sectional view of the

movable contact assembly, substantially as indicated by the line and arrows 8—8 of Fig. 7.

A selector switch 50 adapted to be used in the lighting system of an automobile is fully illustrated in Figs. 1 to 8 inclusive. With particular reference to these figures of the drawings, the selector switch comprises a casing including a pair of housing members one of which is a cupped housing 72 that telescopically engages a terminal cover 74. The cover has a pair of webs or mutilated flanges 76 internally grooved at 78 to snap over a ridge 80 provided by the terminating flange of the switch case 72. The switch case member 72 is provided with a conduit clamp or support 82 in the form of a cylindrical extension extending from the side wall of the casing, and is secured thereto by any convenient means, the conduit support being positioned substantially opposite the medial line of the terminal cover 74. Cooperating with the conduit support is a semi-cylindrical shield portion 84 carried by the cover 74 that overlies the extension 82.

The detail construction of the switch casing 72 is illustrated in Figs. 3 and 5, in which it will be seen that the flange of the cup 72 is flared outwardly at 86 to join an enlarged cylindrical portion 88, within which is disposed a dielectric member 90 constituting a partition within the housing separating the switch compartment from the terminal compartment. The dielectric member 90 moldably or otherwise secures therein, electric conductive elements forming switch contacts on the switch side of the dielectric member and terminal members on the side adjacent the cover 74. These electrically conductive elements constitute the fixed switch contacts 28, 32, 36, 40, 44, 48, 54, 60 and 64 of the selector switch. These contacts are disposed substantially as indicated in the plan view of the switch back as illustrated in Figs. 4 and 6. The switch back 90, when disposed within the enlarged portion 88 of the switch casing, will be seated against the flared portion 86 where it is retained by means of a spring ring 92, disposed within the groove of the cup case providing the rib 80 heretofore referred to, and the case 72 may provide means for anchoring the spring ring, which may include the apertures 94 through which the spring ends or angular extension 96 may project.

The switch structure enclosed by the casing 72 constitutes a shaft element or coupler 98 adapted to mate up with an actuator element 99, and by which motion may be transmitted to a movable contact assembly 100. The contact assembly includes a dielectric plate 102 of annular form, 55

and about whose central aperture 103 there is mounted a contact ring 104 carrying the contact points 106. The ring is supported from the plate 102 by means of axially extending legs 108 bent from the plate of the ring 104 to extend through apertures 110 of the plate 102 where their ends are bent over as at 112. A spring 114 of large diameter is disposed between the plate 102 and the ring 104 and tends to space the same or force them apart. The spring engages the contact ring directly beneath the contact points 106 and is maintained in that particular relation by means of a plurality of axially extending lugs 116 formed from the inner periphery of the ring 104, 15 and disposed just within the inner confines of the spring 114. A pair of arc-like contact strips 118 are mounted upon the plate 102 near the outer periphery thereof, and in substantially diametrically opposed position, one with respect to the other. These contact strips 118 are also floatingly or yieldingly carried by the plate 102 as is the ring 104. That is accomplished by means of rivets or studs 120 passing through the plate 102 and loosely through the strips 118 against which the ends of the rivets are peened over. The rivets or studs carry contact urging springs 122 that tend to separate the contact strips 118 from the plate 102. Both of these contact strips 118 provide a plurality of contact points 124.

30 The fixed switch contacts of the selector switch are arranged in two concentric rows. The outer row contains the contacts 36, 44, 64, 40 and 60 while the inner row contains the contacts 28, 48, 54 and 32. It should be noted that the contact points 106 and 124 of the various contact members carried by the assembly 100 are also arranged in two substantially concentric rows, and that they are so characterized that the inner contact member 104 with its contacts 106 may be superimposed upon the inner row of switch contacts provided by the dielectric member 90, while the contacts 124 provided by the members 118 may be superimposed over the outer row of the fixed contacts provided by the switch back. Thus, rotation 40 of the movable contact assembly will cause the contact members to travel in a circulatory path over the inner surface of the switch back and in so doing will engage one or more of the contact members in the respective rows of fixed contacts.

45 50 Rotation of the contact assembly is accomplished by means of the controller 99 hereinbefore referred to, that is in coupled relation with the shaft element 98.

The shaft element 98 is of tubular form and has 55 its ends provided with bearings 126 and 128 in the switch back and bottom wall of the switch casing respectively. If desired one or both of the shaft ends may be reduced in cross section so as to provide shoulder portions, but at any rate one 60 end of the shaft portion 98 is provided with a pair of flats or other provision to mate with a non-rounded aperture 132 in a driving plate 136. The driving plate 136 provides a plurality of driving lugs 138 upstanding or projecting from the 65 plane thereof, which lugs are formed to provide shouldered portions 140 to be engaged by apertures 142 in the contact carrying plate 102. The driving lugs 138 with the shoulders provide means 70 for spacing the movable contact assembly 100 from the driving plate 136.

At points intermediate the driving lugs, the plate 136 is provided with a circular row of apertures 144 that are disposed over a row of apertures 146 provided by the bottom of the switch 75 case 72, and which rows of apertures are substan-

tially concentric to the shaft bearing 128. Disposed within the space between the driving plate 136 and the contact carrying plate 102 there is a detent plate 148 whose periphery is notched at 150 for reception of the driving lugs 138 of the driving plate. The detent plate 148 has a central bore 152 of sufficient diameter to be passed over the larger portion of the shaft element 98, and so as to be loosely associated therewith and between the driving lugs 138. The detent plate 148 is also provided with a plurality of detent provisions such as rounded or spherical bosses 154 adapted to mate up with the apertures 144 of the driving plate 136. The apertures 144 are of such magnitude, and the depth of the detent provisions 154 are such that the bosses 154 will project entirely through the apertures 144 and across a space provided by a shim or spacer 156, disposed between the drive plate 136 and the bottom wall of the switch case 72, with the rounded ends of the detent provisions 154 nicely seating in one or another of the apertures 144.

A construction of this kind provides a detent plate 148 that is loosely confined about the shaft 98, and between the contact carrying plate 102 and the driving plate 136. Means are provided to maintain the detent plate seated against the driving plate, and includes a spring 158 embracing the shaft 98. One end of the spring is seated in a spring cup 160 disposed about the bearing end 126 and against the switch back member 90, and the other end of the spring is disposed over the axially flared rim 152 of the plate 148. Providing for this, the central aperture through the contact assembly 100 is of sufficient diameter to 35 allow the free passage of the spring 158.

A mounting bracket 164 of any desired form may be secured to the switch casing 72 and provides means by which the selector switch may be mounted at the lower end of the steering column, 40 or as may otherwise be desired. The controller 99 will then constitute a rod extending through the steering column and having its lower end in driving relation with the shaft element 98, which may embrace the feather and groove connection 166. 45 When so mounted, rotation of the controller 99 will manifest in a rotary movement of the movable contacts over the fixed contacts of the switch back 90. The switch contacts have electrical communication with suitable leads, as by means of the terminal screws or other fixtures 168 with various lamp connections and with a suitable controller switch, described in our copending application referred to above for controlling the major circuits of the lighting system. 50

While the embodiment of the present invention as herein disclosed, constitutes a preferred form, it is to be understood that other forms might be adopted, all coming within the scope of the claims which follow. 60

What is claimed is as follows:

1. A lighting switch comprising in combination, a casing member, a switch back closing the casing member and providing a plurality of fixed contacts, a movable contact assembly within the 65 casing member for cooperation with the fixed contacts, a switch actuator, and means journaled in the casing member and the switch back coupling the actuator to the movable contact assembly, said means comprising, a tubular shaft, 70 a perforated driving plate having a plurality of driving lugs and having a sliding fit over the tubular shaft for rotation and in driven relation with said tubular shaft, means provided by the movable contact assembly for receiving the ends 75

5 of the driving lugs, the contact assembly and the driving plate being relatively spaced apart by said driving lugs, a detent plate disposed in the space between the contact assembly and the driving plate, said detent plate adapted for axial movement along the tubular shaft and providing detents extending through the perforations of the driving plate for cooperation with recesses in the bottom of the switch casing, and means surrounding the shaft and disposed between the back and the detent plate and through the contact assembly for urging the detent plate into a ratcheting relation with the switch casing.

10 2. A switch comprising in combination, a housing; a closure for the housing; conducting elements carried by the closure and arranged in two concentric rows, said conducting elements providing fixed contacts exposed within the housing, the outer row of contacts being arranged in spaced groups of contacts; a movable contact assembly journalled for rotation within the housing and including a contact carrier, a contact ring supported by the carrier, means provided by the ring and carrier whereby the ring is moved axially with respect to the carrier and rotated therewith and adapted to move over the inner row of fixed contacts, contact strips insulated from each other and disposed outside of the ring, each strip adapted to move over one group of fixed contacts of the outer row, means for supporting each of the contact strips from the carrier, and spring means for urging the ring and the strips toward the closure, the ring and strips having a plurality of contact points, for engagement with the fixed contacts.

15 3. A lighting switch comprising in combination; a cup-shaped housing; a switch back carried by the housing; conducting elements carried by the switch back and providing fixed contacts within the housing and arranged in two concentric rows, said outer row of contacts being arranged in oppositely disposed groups of contacts; a movable contact assembly for bridging selected ones of the fixed contacts; an actuator as-

20 sembly within the housing for driving the contact assembly, said actuator assembly comprising a shaft journalled in the switch back and the bottom wall of the housing; a driving plate fitted over but nonrotatable with respect to the shaft and providing a plurality of apertures arranged in a row concentric with the axis of the shaft; a detent plate disposed about the shaft and having detent provisions projecting through the driving plate apertures, the bottom wall of the housing having a circular row of apertures concentric with the journal of the shaft; and spring means surrounding the shaft and disposed between the back and the detent plate for urging the detents thereof through the apertures of the driving plate and into the apertures of the bottom wall of the case.

25 4. A lighting switch comprising in combination; a cup-shaped housing; a closure for the housing; conducting elements carried by the closure and providing fixed contacts arranged in two concentric rows; movable contacts enclosed within the housing adapted for engagement with selected ones of the fixed contacts; a contact supporting plate; means for yieldingly mounting the movable contacts thereon and in concentric rows, means for driving the contact supporting plate, said last mentioned means including a tubular shaft extending through the supporting plate and having its ends journalled in the switch back and the bottom wall of the housing; a driving plate secured to the shaft and having axially extending lugs for engaging the contact supporting plate and for spacing the same from the plate; a detent plate disposed between the driving plate and the contact supporting plate, the housing bottom and driving plate both being apertured in registration with the detents carried by the detent plate; and means surrounding the shaft and engaging the closure and the detent plate and adapted to force the detents thereof into the registering openings.
